W. A. Ruff

UNITED STATES PATENT OFFICE.

DAVID GROVE, OF ELLSWORTH, ILLINOIS.

REEL FOR WINDING WIRE.

SPECIFICATION forming part of Letters Patent No. 414,809, dated November 12, 1889.

Application filed July 16, 1889. Serial No. 317,709. (No model.)

To all whom it may concern:

Be it known that I, DAVID GROVE, of Ellsworth, in the county of McLean and State of Illinois, have invented certain new and useful Improvements in Reels for Winding Wire; and I do hereby declare the following to be a full, clear, and exact description of the invention, such as will enable others skilled in the art to which it appertains to make and use the same.

My invention relates to an improvement in reels for winding and paying wire, the object of the same being to provide a device of the above character which shall combine means whereby the speed at which the wire is paid out may be conveniently and effectually governed by the operator.

A further object is to provide a machine of the above character which shall be simple and economical in construction and durable and efficient in use.

A further object is to provide means for regulating the distribution of wire upon the reel.

With the above ends in view my invention consists in certain features of construction and combinations of parts, which will be hereinafter fully described, and pointed out in the claim.

In the accompanying drawings, Figure 1 is a view in side elevation showing the brake-bar, &c., and Fig. 2 is a top plan view.

The body of the machine is suitably supported on the axle A, journaled in wheels B by means of the shafts C, secured to said axle. The side boards D are secured to said shafts, and are provided with grooves E in their upper edges to receive the shaft F. On this shaft is removably secured the spool G, which is provided with crossed end bars H at each end, the inner bar of each pair being beveled, as shown, to facilitate the winding of the wire. The spool is slipped upon the shaft or axle and locked thereto by means of the feathers f on said shaft, which engage with grooves g in the spool. A nut h at the opposite end of the spool is screwed up against the outer bar H and prevents the spool from slipping off the feathers. The shaft F is removably held in the grooves by means of the hinged clips I. One end of the shaft is provided

with the crank J for operating the same, and is further provided between the side board and the crank with the ratchet K, with which the pawl L engages and holds the said shaft 55 in position when the wire is being wound thereon. A brake-bar M is pivoted to the side board, as shown, the free end of which engages the collar N on the shaft. The lever O is pivoted below the brake-bar, and is connected therewith by means of the rod P. To the cross-bars Q is pivoted the lever-bar R, one end of which plays on the cross-bar S, in which are secured the posts T to limit the play of the lever-bar R. The rear end of the 60 lever-bar R is provided with upright rollers U, journaled therein, the upper ends of said rollers being journaled in the braces V, which are secured to the lever-bar—one on each side. The said braces are curved at their upper ends in the direction of each other. A horizontal roller W is journaled in the braces V near the face of the bar and in the rear of the rollers U, for the purpose of facilitating the handling of the wire. Horizontal rollers 70 Y are journaled in the rear ends of the side boards D in front of the rollers U. The object of the lever-bar is to enable the operator to wind the wire uniformly upon the spool by shunting the lever from one side to the other. 80

By using rollers the barbs of the wire will not catch in its passage to the spool. The rollers should be made of metal, or if wood is used it should be covered with metal.

Having fully described my invention, what I 85 claim as new, and desire to secure by Letters Patent, is—

In a wire-reel, the combination, with a removable axle and a removable spool engaging said axle, of a shunting-lever pivotally secured below the spool and carrying a horizontal roller and vertical rollers for guiding the wire, and horizontal rollers located independently in front of the vertical rollers, substantially as shown and described. 95

In testimony whereof I have signed this specification in the presence of two subscribing witnesses.

DAVID GROVE.
